PROTECTIVE HOOD

Joseph De Grazia, Washington, D. C.

Application January 8, 1947, Serial No. 720,892

2 Claims. (Cl. 2—204)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

My invention relates to a protective hood, and more particularly to a head covering consisting of a flat sheet of flexible material and drawstring means arranged in such a manner that the sheet can be draped about the head of the wearer.

Hoods, head scarves and similar items of apparel have been used for immemorial times, and are well known to the art. A shortcoming common to most of them is the difficulty of fastening them securely about the head of the wearer to prevent accidental displacement of the hood.

This invention thus has as one of its principal objects a hood which is so dimensioned that it will adequately protect the head and neck of the wearer, and which is securable in place by simple drawstring means arranged in a novel fashion.

Another object of this invention is a protective hood, the body of which may be inexpensively fabricated from a single flat blank of flexible sheet material.

A further object of this invention is a compactly foldable item of apparel, flat when not in use, and conforming to the shape of the head of the wearer when in use.

These and other objects of the present invention will appear more fully as the following description of a preferred embodiment thereof proceeds in connection with the appended drawings, wherein:

Fig. 1 is a perspective view of a head covering in accordance with my invention, in use;

Fig. 2 is a perspective view of a modification of the device illustrated in Fig. 1, showing a head covering in accordance with my invention as an integral part of a raincape;

Fig. 3 is a plan view of the head covering illustrated in Fig. 1, when not in use; and

Fig. 4 is a detailed sectional perspective view of a portion of the head covering shown in Fig. 3 at the location of line 4—4 thereon.

More particularly, reference numeral 10 denotes a flat sheet of flexible material, constituting the body of the head covering. The size of sheet 10 must be sufficiently large to protect the head, and preferably part or all of the shoulders of the wearer, and thus is somewhat larger than a conventional head scarf. As a head and shoulder covering, sheet 10 has a substantially straight edge 11 and an arcuate edge 12. The edge 11 forms an uninterrupted chord joining the ends

2

of the arc of edge 12. The arc of edge 12 should preferably be so curved that when the covering is draped about the shoulders of the wearer and the drawstrings (which will be presently discussed in greater detail) are tightened, the periphery of the lower edge will be substantially equidistant from the ground on the body of an average-size wearer.

To drape sheet 10 about the head of the wearer, it is equipped with a pair of drawstrings 13, 14. Drawstrings 13 and 14 are endwise fastened to sheet 10 at spaced points 15, 16 at or near edge 11, and at a sufficient distance from the center of edge 11 to permit the portion of edge 11 bounded by the aforementioned fastening points to frame the head of the wearer. To assure symmetrical draping of the head covering, points 15 and 16 are equidistant from the center of edge 11. The path of drawstrings 13 and 14 is defined by arcuate drawstring-housing 17 which has its terminals at points 15 and 16. Drawstring-housing 17 is suitably secured to sheet 10 by heat-sealing the parallel edges 18, 19 of the former to the latter, or by stitching or by other suitable means. Arcuate drawstring housing 17 should run substantially concentric with arcuate edge 12 of the sheet, in order that the latter may drape around the body of the wearer in a graceful manner. By heat-sealing the drawstring housing 17 to the sheet, the strength of the latter is increased, and weakening of the structure by needle holes, which would result from conventional stitching, is avoided. Drawstrings 13 and 14 thus run parallel in an arcuate path defined by edges 18 and 19 of drawstring-housing 17 and by housing 17 and sheet 10 themselves. The free end of drawstring 14 extends beyond and protrudes from the terminal of housing 17 near point 16, the fastening point of drawstring 13. Likewise, the free end of drawstring 13 extends beyond and protrudes from the terminal of housing 17 near point 15, the fastening point of drawstring 14.

An elongated edge strip 20 is joined to sheet 10 along its straight edge 11, preferably by heat-sealing. Edge strip 20 serves as a reinforcement of edge 11 and as a means for affixing the fast ends of drawstrings 13 and 14 to the hood; as shown in Figures 3 and 4, edge strip 20 is locally separated from sheet 10 at drawstring attachment points 15 and 16 in order to enable drawstrings 13 and 14 to be conveniently tied to edge strip 20.

The area A of sheet 10, enclosed by edge 18 of housing 17 and by that portion of edge 11 which lies between points 15 and 16, thus con-

stitutes the head covering, while area B of sheet 10, which lies beyond housing 17, constitutes a shoulder covering (as shown in Fig. 1).

When in use, that portion of edge 11 of sheet 10 which lies between drawstring terminals 15 and 16 frames the face of the wearer, while housing 17 surrounds the neck of the wearer. By adjusting drawstrings 13 and 14, housing 17 and that portion of sheet 10 which is fastened thereto are suitably tightened to provide a secure fastening of the hood and a tight seal against rain, snow, etc.

While the size of area A of sheet 10 is predetermined by the surface of a human head, the size of area B may be chosen at will. If no shoulder protection is desired, edge 12 of sheet 10 may be made to coincide with outer edge 19 of housing 17, and area B thus eliminated altogether. If the average distance of edge 12 of sheet 10 from housing 17 is in the order of 1 ft., more or less, the outer area B of sheet 10 provides an adequate shoulder drape. Area B may be still further enlarged by increasing the average distance between edge 12 and housing 17 to several feet, which results in the raincape structure shown in Fig. 2, comprising a head covering A' corresponding in size to portion A of the embodiment shown in Fig. 1, but having a large body-covering portion B' integral with portion A'. Buttons or analogous conventional fastening means (not shown) may be provided at the fly front of such a cape.

Any waterproof or water-repellant flexible material is suitable for the manufacture of the protective hood described in the foregoing part of my specification. For rapid and secure assembly of body and drawstring-housing of the hood, I prefer the use of conventional plastic heat-sealable material for both, but do not desire to limit the scope of my invention to such material.

I am aware that hoods, preformed in three-dimensional shape to correspond roughly to the configuration of a human head, and equipped with drawstring means, are known to the art, and I do not desire to encompass such devices within the scope of my invention.

It will thus be seen that I have provided a simple, inexpensive and durable protective covering for the head and adjacent body portions of the user, which can be conveniently carried in a pocket, handbag, pouch, or inside a hat when not in use. Its applications are necessarily wide; while eminently useful in protecting members of the military forces against inclemencies of the weather, it is equally suitable for analogous use by other persons. Obviously, the preferred embodiment of my invention described above and illustrated in the drawing, as well as the modification thereof likewise described in the aforementioned places, is capable of changes in dimensions or minor variations in arrangement of the component parts without departing from the spirit of my invention, which variations thus fall within the scope thereof. I therefore desire to be limited in the coverage of my invention only by the appended claims.

I claim:

1. A head covering comprising a flat sheet of flexible material having a straight edge and an arcuate edge, said straight edge forming a substantially uninterrupted chord joining the ends of said arcuate edge, arcuate drawstring-housing means associated with said sheet substantially concentrically with said arcuate sheet edge, said means ending in a pair of terminals located proximate said straight edge of said sheet, and a pair of parallel drawstrings in said housing means, one of said drawstrings being fixed proximate one of said terminals and having a free end extending beyond the other of said terminals, and the other of said drawstrings being fixed proximate said other terminal and having a free end extending beyond the first-named terminal, said straight edge being adapted to conform to the contours of the face of the wearer and said arcuate edge being adapted to drape about the body of the wearer below the neck substantially equidistantly from the ground along the periphery of said arcuate edge when said drawstrings are tightened.
2. A head covering comprising a flat sheet of flexible material having a straight edge and an arcuate edge, said straight edge forming a substantially uninterrupted chord joining the ends of said arcuate edge, an elongated edge strip joined to said sheet along said straight edge, arcuate drawstring-housing means associated with said sheet substantially concentrically with said arcuate sheet edge, said means ending in a pair of terminals located proximate said straight edge of said sheet, and a pair of parallel drawstrings in said housing means, one of said drawstrings being fixed to said edge strip proximate one of said terminals and having a free end extending beyond the other of said terminals, and the other of said drawstrings being fixed to said edge strip proximate said other terminal and having a free end extending beyond the first-named terminal, said straight edge being adapted to conform to the contours of the face of the wearer and said arcuate edge being adapted to drape about the body of the wearer below the neck substantially equidistantly from the ground along the periphery of said arcuate edge when said drawstrings are tightened.

JOSEPH DE GRAZIA.
